ABSTRACT: A container is provided with air vent means having gravity actuated means controlling the air vent means to provide for venting both when the container is upright or inverted.

VENTED CONTAINER

CROSS REFERENCE

This is a continuation-in-part of pending U.S. Pat. application Ser. No. 616,961 filed Feb. 17, 1967, now U.S. Pat. No. 3,459,245.

BACKGROUND OF THE INVENTION

In certain application, it is desirable to employ a single container for supplying and withdrawing liquid from a closed system, *i.e.*, a system which tightly connects to the container and prevents the ready entry of air into the container or passage of air from the container during emptying and filling the container respectively. The primary purpose of this invention is to provide means for the ready supply of air to a container when the container is inverted to withdraw liquid from it into a closed system and to permit the passage of air from the container when it is upright and being supplied with liquid from a closed system.

SUMMARY OF THE INVENTION

A container for discharging liquid to or receiving liquid from a closed system has air vent means with one end exposed to the atmosphere adjacent the top of the container and with the other end adjacent the bottom of the container. Intermediate its ends, the vent means has a passage opening to the interior container, the said passage being controlled by gravity-actuated means to close the passage when the container is inverted and open it when the container is upright.

DESCRIPTION OF THE DRAWINGS

FIG. 1 is a front elevation, partially broken away, of a container in accordance with the invention;

FIG. 2 is a rear elevation of the container of FIG. 1, partially broken away, in the inverted position; and

FIG. 3 is a vertical section, partially broken away, of the top of the container in FIG. 1 fitted with a cap.

DESCRIPTION OF PREFERRED EMBODIMENT

A container 2 has a body 4 and a threaded neck 6 to which there is threadably secured a top member 8. Member 8 is turned down on neck 6 so as to press a washer 10 against the top 12 of container 2 to form a seal. Top member 8 has a neck 14 which communicates with the interior of container 2 through an opening 16.

A tube 20 is secured by a pressed fit in opening 22 in top member 8. Tube 20 is secured by a pressed fit to tube 24 which is threadably secured at 26 to a cup-shaped member 28. A disc 32 is threadably secured at 34 to the interior of cup-shaped member 28. Disc 32 is provided with a plurality of openings 36 and is threadably secured to a tube 38 as indicated at 40. Openings 36 are adapted to be closed by a washer 42 which fits slidably about tube 38. A bead 44 on tube 38 limits the travel of washer 42. Tube 38 preferably terminates near the bottom of container 2.

A cap member 50 is threadably secured as indicated at 52 to

top member 8. Top member 50 has a recessed portion 54 which snugly engages neck 14 of top member 8. Communication to the atmosphere for tube 20 is provided by a passage indicated at 56 which is connected to the atmosphere by a plurality of passages 58. Cap member 50 is provided with a neck 60 for connection to a closed system a part of which typically may be the flexible tube indicated at 62.

As shown in FIG. 3, cap portion 50 may be removed and replaced by a closure cap 66 which can be threaded to top member 8 as indicated at 68 to prevent the passage of liquid into or out of container 2.

OPERATION

When the container 2 is receiving liquid, for example, from hose 62, air is vented to the atmosphere from the interior of the container by passing through openings 36 into cup shaped member 28 and thence through tube 24, tube 20, passage 56 and openings 58 to the atmosphere. It will be noted that the force of gravity keeps washer 42 against bead 44 and hence from impeding the flow of air through openings 36.

On the other hand, when liquid is flowing from container 2 with the container in an inverted position as shown in FIG. 2, washer 42 by the force of gravity is moved against disc 32 to close openings 36 and hence prevent liquid from flowing therethrough. Air moves into the bottom of the container by passing through openings 58, passage 56, tube 20, tube 24, cup shaped member 28 and tube 38. Thus, in accordance with the invention, the container is readily usable with a closed system either for discharging a liquid to the system or receiving a liquid from the system.

It will be understood that the above described embodiment is illustrative and is not limiting.

We claim:

1. In an open neck container for discharging liquid to or receiving liquid from a closed system the improvement comprising:
a container top mounted on the neck of the container and having a passage for the flow of liquid into and out of the container and a second passage communicating with the atmosphere;
a conduit having one end connected to said second passage and the other end adjacent the bottom of the container; said conduit having a passage opening to the interior of the container intermediate its ends; and
gravity actuated means to close said third mentioned passage when the container is inverted and open it when the container is upright.
2. The device of claim 1 in which the gravity actuated means is slidably mounted on the conduit.
3. The device of claim 1 in which the conduit includes a pair of tubes;
a fitting connecting the ends of said tubes in spaced apart relation; and
the third mentioned passage being in said fitting and in communication with the interior of said tubes and the interior of the container.
